(57) **CLAIM**

I claim the ornamental design for an axe, as shown and described.

DESCRIPTION

FIG. 1 is a front view of the claimed design;

FIG. 2 is a left side view of the claimed design of FIG. 1;
FIG. 3 is a right side view of the claimed design of FIG. 1;
FIG. 4 is a bottom view of the claimed design of FIG. 1;
FIG. 5 is a bottom perspective view of the claimed design of FIG. 1;

FIG. 6 is a right side perspective view of the claimed design of FIG. 1; and,

FIG. 7 is a left side perspective view of the claimed design of FIG. 1.

The broken lines depict portions of the axe in which the design is embodied that are not considered part of the claimed design.

1 Claim, 7 Drawing Sheets
